(Cl. D48—23)

To all whom it may concern:

Be it known that we, Michael Henry Kruger, residing at Chestnut Hill, in the county of Middlesex and State of Massachusetts, and Maurice Gilman, residing at Chelsea, in the county of Suffolk and State of Massachusetts, both citizens of the United States, have invented a new, original, and ornamental Design for a Lamp Fixture, of which the following is a specification, reference being had to the accompanying drawing, forming a part hereof.

Fig. 1 is a perspective view of the lamp fixture showing our new design.

Fig. 2 is a bottom plan view of the same.

Fig. 3 is a side elevation of the same.

We claim:

The ornamental design for a lamp fixture, as shown.
